AUTOMATIC FIDELITY CONTROL

John S. Starrett, Livingston, N. J., assignor to
Radio Corporation of America, a corporation of
Delaware

Application November 10, 1933, Serial No. 697,388

6 Claims. (Cl. 250—20)

My present invention relates to radio receivers, and more particularly to transmission control circuits for radio receiver signals.

Hiss and high frequency noise reproduction which takes place along with the reproduction of high modulation frequencies constitute one of the chief difficulties experienced in high quality radio receivers. These difficulties are usually encountered when receiving from distant stations, or those providing a low field strength at the receiver. To eliminate, or minimize, these effects as has commonly been the practice to supply a manual "tone control", such as an electrical network, on the receiver, usually on the input or output of the output tube. Such a tone control mechanism is varied to increase or decrease the attenuation of the higher audio frequencies. The usual form of a tone control network in the prior art is a capacity of 0.01 to 0.05 microfarad connected in series with a variable resistor of 50,000 or 100,000 ohms, and this series circuit is usually bridged across the primary of the audio output transformer.

It is one of the main objects of the present invention to secure an automatic control of the aforementioned high audio frequency attenuation function, a receiver embodying the present invention utilizing a photo-sensitive instrumentality in place of the variable resistor usually employed in the tone control path.

Another important object of the present invention is to provide a means for automatically controlling the fidelity of reproduction of a radio receiver wherein a selenium cell is utilized as a variable resistor in a tone control network disposed in the audio frequency amplifier network, the resistance of the cell being regulated by a light source whose intensity varies with the automatically controlled bias on the high frequency network preceding the audio frequency amplifier.

Another object of the invention is to provide in a superheterodyne receiver a control arrangement which simultaneously regulates the gain of the radio frequency and intermediate frequency amplifiers of the receiver and the fidelity of reproduction of the receiver, the fidelity control being accomplished by a photo-sensitive device functioning as a variable impedance in the audio frequency amplified network.

Still other objects of the invention are to improve generally the simplicity and efficiency of radio receivers employing automatic volume control and fidelity control arrangements, and especially to provide a receiver of this type which

is not only reliable in operation, but economically manufactured and assembled.

The novel features which I believe to be characteristic of my invention are set forth in particularity in the appended claims. The invention itself, however, both as to its organization and method of operation, will best be understood by reference to the following description taken in connection with the drawing, in which I have indicated diagrammatically a circuit organization whereby my invention may be carried into effect.

Referring now to the accompanying drawing, which diagrammatically shows a conventional and well-known type of superheterodyne receiver, it is pointed out that the essential elements of the receiver include the usual grounded antenna circuit 1, a tunable radio frequency amplifier 2, a combined first detector-local oscillator 3, an intermediate frequency amplifier 4, a second detector 5, and an audio frequency amplifier 6. The first detector network 3, while described as employing a single tube for local oscillator and first detector functions, can, of course, be replaced by a network employing two independent tubes for these two functions.

In any event, the tuning means of the amplifier 2 and the network 3 are arranged for unit-control adjustment, and this is designated by the dotted line 7. The intermediate frequency output of the network 3 is impressed upon the intermediate frequency amplifier 4 through the tuned network 8, and the resonant network 9, tuned to the intermediate frequency, couples the amplifier 4 to the second detector 5. The audio transformer 10 couples the second detector 5 to the audio amplifier 6, while the audio output transformer 11 couples the amplifier 6 to any well known type of reproducer, such as a loud speaker.

Of course, one or more stages of audio frequency amplification may be disposed between the second detector 5 and the output tube 6, and the tube 6 need not be of the pentode type. The gain of the amplifiers 2 and 4 is regulated automatically in an inverse sense with variations in carrier amplitude of received signals by means of an automatic volume control tube 12, whose anode circuit is connected to the grid circuit of tube 2 through a direct current connection 13. The direct current connection 14 connects the grid circuit of tube 4 to the anode of tube 12, and also to the grid of an automatic fidelity control tube 15. The tube 12 has been designated as

"AVC", and the tube 15 has been designated as "AFC".

Signal energy is impressed upon the grid of tube 12 through a connection 16, which includes 5 a radio frequency condenser 17. The cathode of tube 15 is connected to the cathodes of tubes 2 and 4 through a connection 18. The voltage supply source for the tubes 12, 15 and 6 is only shown because the voltage sources for the remaining tubes are conventional. The last named 10 voltage supply source is not shown, but the bleeder connected across it is represented by the resistors 19, 20, 21, 22, and 23.

The junction of resistors 20 and 21 is grounded, 15 and the resistor 24 is connected between its ground point and the direct current connection 14. The cathode of tube 12 is connected between the junction of resistors 19 and 20, while the cathode of tube 15 is connected between the 20 junction of resistors 21 and 22. The anode of tube 15 is connected to the junction of resistors 22 and 23 through a filament 25, the positive terminal side of resistor 23 being connected to the anode of the audio output tube 6 through 25 the primary of the output transformer 11. The grid and cathode of tube 12 are connected through resistor 19 and the resistor 19', and the junction of resistors 19' and 19 is connected to the negative side of the voltage supply source.

30 The tone control, or high audio frequency attenuation path, is connected across the primary of transformer 11, and this path includes a variable impedance 30 in series with a condenser 31. Variable impedance 30 is a photo-sensitive 35 element, such as a selenium cell, and is disposed adjacent the filament 25. It is believed only necessary to represent the selenium cell in conventional form, as its specific construction is well known to those skilled in the art.

40 The selenium cell 30 and the filament 25 are preferably sealed into a single bulb 32, and mounted in a standard four pin base, not shown. The exterior, or interior, surface of the bulb 32 is coated with an opaque film 33 to exclude light 45 from outside sources. By way of illustration, it is pointed out that the condenser 17 may have a capacity of 0.001 microfarad, the resistor 24 may have a resistance of 0.5 megohm, the condenser 31 may have a capacity of 0.01 to 0.05 microfarad, 50 and the variable resistor may have a resistance of 50,000 or 100,000 ohms.

The operation of the arrangement shown will 55 now be described, it being first pointed out that the chief object is to secure automatic control of the attenuation path 30, 31 by controlling the resistance of element 30 from the light source 25, the intensity of the light admitted by filament 25 varying with the automatically controlled bias on 60 the amplifiers 2 and 4. The AVC tube grid is fed with signal energy from the input of the second detector 5. Normally, that is with no signal input to the detector 5, the AVC tube 12 is biased to 65 cut off. As the signal input through the condenser 17 increases, the space current flow through tube 12 increases, and, therefore, the plate current flow through the resistor 24 increases. The increase in plate current flow 70 through resistor 24 imposes a negative bias upon the grids of amplifiers 2 and 4. Thus, for a strong local signal, the direct current voltage across the resistor 24 will be from 35 to 40 volts, and with a weak signal will be substantially zero.

The voltage across resistor 24 also controls the plate current flow through the fidelity control tube 15. Therefore, it will be seen that as the

signal input increases the negative bias on tube 15 increases, and the flow of current through the plate circuit of tube 15 decreases. Accordingly, the heating of the filament 25 will vary with the variation in plate current flow through tube 15. 5 That is to say, the plate current of tube 15 controls the brilliancy of illumination of the lamp filament 25, the light from which falls upon the selenium cell 30. With a strong signal the lamp filament will be dark and the resistance of the 10 selenium cell 30 high, and this means that the attenuation of the higher audio frequencies will be a minimum. For a weak signal, on the other hand, the illumination of the selenium cell becomes greater and the cell resistance is lowered, 15 with the result that the attenuation of the higher audio frequencies will be maximum.

It will, therefore, be seen that in the no-signal condition, the tube 15 has its maximum plate current flow and the filament 25 emits maximum 20 light. This is desirable, since, with no signals or weak signals coming in, the amplifiers 2 and 4 are operating with maximum efficiency and amplify background noise impulses to an annoying extent. In this condition the resistance of cell 25 30 is at a minimum and the attenuation of the higher audio frequencies is at a maximum, which means that the hiss and high frequency noise reproduction is substantially eliminated, or minimized.

30 While I have indicated and described one system for carrying my invention into effect, it will be apparent to one skilled in the art that my invention is by no means limited to the particular organization shown and described, but that 35 many modifications may be made, without departing from the scope of my invention, as set forth in the appended claims.

What I claim is:—

1. A background noise suppressor arrangement 40 for a radio receiver which comprises at least two successive high frequency amplifiers, a detector and an audio frequency amplifier, said suppressor arrangement including an amplifier gain control tube having a direct current connection between 45 its anode circuit and the grid circuits of said amplifiers, a signal path between said detector and the grid circuit of the gain control tube, a noise suppressor tube having its input electrodes connected to the anode circuit of said gain control tube, a light source in the anode circuit of the suppressor tube, and an audio frequency attenuation path in the output circuit of the audio amplifier, said attenuation path including a 50 photo-sensitive element whose impedance depends upon the light emitted from said light source.

2. In an arrangement, as defined in claim 1, said photo-sensitive device consisting of a selenium cell, said suppressor tube having voltage constants such that the illumination from said light source is a maximum when substantially no signals are impressed on the grid of said gain control tube, whereby the impedance of said selenium cell is a minimum and the higher audio frequencies corresponding to undesired background noise impulses are by-passed out of the audio amplifier output circuit.

3. In combination with a signal transmission tube a demodulator, and a demodulated signal utilization network, means responsive to variations in received signal intensity for regulating the gain of said tube in a sense to maintain the signal input to the demodulator substantially constant, an audio attenuation path operatively 70 75

associated with the utilization network, the path including a photo-sensitive element and means operative upon the gain of said tube becoming substantially a maximum, for varying the impedance of said element in a decreasing sense whereby the higher modulation frequencies are efficiently transmitted through said path.

5 4. In combination with a radio receiver provided with a high frequency amplifier and a rectifier, an automatic volume control tube having a radio frequency signal connection between its grid and the rectifier, an automatic fidelity control tube having its input electrodes directly connected across an impedance in the plate circuit 10 of the volume control tube, means in circuit with the input electrodes of the volume control tube for biasing the volume control tube substantially to cut-off when substantially no signals are impressed upon said rectifier, an audio frequency network coupled to said rectifier, an audio frequency attenuation path connected to said network and including an element which has a variable impedance, and means in the plate circuit 15 of said fidelity control tube for controlling the impedance of said element in said attenuation path, said variable impedance element consisting of a photo-sensitive device, such as a selenium cell, and said means in the plate circuit of the 20 fidelity control tube consisting of a light source, whose illumination varies with the flow of the fidelity control tube plate current.

25 5. In combination with a radio receiver provided with a high frequency amplifier and a rectifier, an automatic volume control tube having a radio frequency signal connection between its grid and the rectifier, an automatic fidelity control 30 tube having its input electrodes directly con-

nected across an impedance in the plate circuit of the volume control tube, means in circuit with the input electrodes of the volume control tube for biasing the volume control tube substantially to cut-off when substantially no signals are impressed upon said rectifier, an audio frequency network coupled to said rectifier, an audio frequency attenuation path connected to said network and including an element which has a variable impedance, and means in the plate circuit 10 of said fidelity control tube for controlling the impedance of said element in said attenuation path, said variable impedance element consisting of a photo-sensitive device, such as a selenium cell, and said means in the plate circuit of the 15 fidelity control tube consisting of a light source, whose illumination varies with the flow of the fidelity control tube plate current.

20 6. In combination with a signal transmission tube, a demodulator, and a demodulated signal utilization network, means responsive to variations in received signal intensity for regulating the gain of said tube in a sense to maintain the signal input to the demodulator substantially constant, an audio attenuation path operatively 25 associated with the utilization network, the path including a photo-sensitive element, and means operative upon the gain of said tube becoming substantially a maximum, for varying the impedance of said element in a decreasing sense whereby 30 the higher modulation frequencies are efficiently transmitted through said path, said last named means being arranged for regulation by said gain regulating means.
